UNITED STATES PATENT OFFICE.

KARL OSCAR ELMQVIST, OF KRISTIANSTAD, SWEDEN.

FIRE-ESCAPE.

1,101,910.

Specification of Letters Patent. Patented June 30, 1914.

Application filed January 27, 1914. Serial No. 814,703.

To all whom it may concern:

Be it known that I, KARL OSCAR ELMQVIST, mechanician, residing at Norra Kaserngatan 64-66, Kristianstad, in the Kingdom of Sweden, have invented certain new and useful Improvements in Fire-Escapes, More Particularly for Fire-Rescue Purposes, of which the following is a specification.

The object of my invention is to provide an improved portable and easily attachable appliance for the conveyance of persons and goods, more particularly for rescue purposes in case of fire.

According to my invention a rope guided over a holding beam is provided at each end with a hanger, hook or the like, which serves for the attachment of a basket or car, arranged to travel on a track or guide rope attached to the beam and to some other convenient support. Preferably I provide a brake-device on the beam, for regulating the velocity of the cars.

The invention is illustrated in the annexed drawings, which show one form of construction, Figure 1 being a perspective elevation, Fig. 2 a side view, with the brake-device omitted, Fig. 3 a front view of the holding beam, Fig. 4 a section on the line A—B of Fig. 3, to a larger scale, and Fig. 5 a front view of the trolley, to a larger scale.

In the drawings, 1 designates a hollow holding beam of iron or hard wood, quadrangular in cross section, having at each end two hooks or eyes 2, fixed to it by means of a frame 3. With the beam arranged as shown in Fig. 1, each of the hooks 2 lying uppermost has attached to it a wire rope 4 dividing into two branches 5 and 6, the branch 6 being attached to a pin 7 and the branch 5 carrying an S-shaped hook 8. Between the other hooks 2, and stakes 9 fixed to the ground, are stretched guide ropes 10. The beam has apertures through which project rollers 11, 12 mounted therein, and a rope 13, to which the cars are attached, passes over these rollers. The rollers 12 are controlled by a brake device comprising two members 14, 15 of U-section pivoted between bearing plates 16 which are mounted on a pivot passing through the beam. The member 14 has pivoted to it, at the end remote from the plates 16, two plates 17 joined to each other by a cross-piece 18. The latter has a tapped eye, whereby it is engaged with the screw-threaded part 19 of a shank 20, the screw 19 being right-handed. The

shank enters an eye in a yoke 21 pivoted to the beam, and has a left-hand thread 22 working in a tapped eye in the member 15. A crank handle 23 on the shank enables the same to be turned, so that the members 14 and 15 are moved to or form each other, and by this means brake shoes 24 carried by these members can be pressed against the rollers 12, or against the rope 13 traveling on same.

The baskets or cars 25 are attached to hangers 26. To the inside surfaces of the branched arms 27 of these hangers are fixed iron plates 28 serving as bearings for rollers 29, 30, mounted within the housings formed by the said plates. The hangers travel on the ropes 10 by means of the rollers 29, and the rollers 30, lying under the ropes, serve as guides preventing tilting of the hangers when they are pulled upward with a light load. Wooden wedges 31 between the plates 28 serve for attaching the ends of the rope 13 and lie between the arms of yokes 32. The rope end passes through the yoke 32 and around the wedge, and is clamped tight in a channel at the upper part by a clamping screw 33 having a pressblock 34. The screw works in a tapped eye 35 carried by the yoke, and has a handle 36. The free rope end issuing from between the plates 28 is wound upon a reel 37 carried by the plates.

For fire-rescue purposes, as from the window 38 shown in Fig. 1, the appliance is taken up by means of the mechanical rescue ladder or the like, and the beam is made fast by fixing the staples 7 into the wall. The hooks 8 may be engaged with a transom or the like, and the beam may be wedged by pieces inserted against the walls. The guide ropes 10 are made fast on the ground by means of the stakes 9 or other convenient means, the general disposition being adapted to the existing circumstances and care being taken to avoid as far as possible flames issuing from lower windows. The ropes 10 may, for example, be carried across to a building on the opposite side of the road. The lower ends thereof may, if convenient, be made fast before the holding beam is fixed. One of the cars is then let down, and the length of rope 13 between the cars is then adjusted, according to the length of the journey, by means of the reels 37 and clamping devices 31, 32, 33. Conveyance of persons and goods from the window can then take

place, each car in turn traveling down loaded, and pulling up the empty car, and the velocity of the cars being regulated by means of the brake.

5 The apparatus is very reliable and easily portable, and can be worked by a single person.

Having thus described my invention what I claim as new and desire to secure by Letters Patent is:—

1. In a fire escape more particularly for fire-rescue purposes, the combination of a holding beam, a conveyer-rope guided on said beam, hangers or hooks for baskets or cars, the said hangers or hooks being provided with plates fixed thereto to form housings for rollers to engage between them track-ropes attached to said beam, for the travel of said hangers or hooks, wedges in the said housings, yokes embracing said wedges, and clamping screws for clamping the said conveyer-rope, when it has passed through said yokes and around said wedges.

2. In a fire escape more particularly for fire-rescue purposes the combination of a holding beam, a conveyer-rope guided on said beam and having at each end means for the attachment of a basket or car, track-ropes attached to said beam, for the travel

of said baskets or cars, beam-fixing-ropes attached to said beam and provided at their ends with staples and hooks and frames at each end of said beam, each frame having two hooks or eyes for the attachment of said track-ropes and said beam-fixing ropes.

3. In a fire escape more particularly for fire-rescue purposes the combination of a holding beam, a conveyer-rope guided on said beam, hangers or hooks for baskets or cars, the said hangers or hooks being provided with plates fixed thereto to form housings for rollers to engage between them track-ropes attached to said beam, for the travel of said hangers or hooks, wedges in the said housings, yokes embracing said wedges, clamping screw for clamping the said conveyer-rope, when it has passed through said yokes and around said wedges and reels carried by the said plates for winding the free ends of said conveyer-ropes.

In testimony whereof I affix my signature in presence of two witnesses.

KARL OSCAR ELMQVIST.
